UNITED STATES PATENT OFFICE.

ADOLPH BERRENBERG, OF SOMERVILLE, MASSACHUSETTS, ASSIGNOR TO
THE BEACON VACUUM PUMP AND ELECTRICAL COMPANY, OF PORT-
LAND, MAINE.

VACUUM-PUMP CONNECTION.

SPECIFICATION forming part of Letters Patent No. 447,275, dated February 24, 1891.

Application filed June 2, 1890. Serial No. 354,046. (No model.)

To all whom it may concern:

Be it known that I, ADOLPH BERRENBERG, of Somerville, in the county of Middlesex and State of Massachusetts, have invented 5 certain new and useful Improvements in Vacuum-Pump Connections, of which the following, taken in connection with the accompanying drawings, is a specification.

My invention relates to a method of connecting and jacketing pipes and cocks, and is particularly adapted to be used in connection with vacuum-pumps for making incandescent lamps, the object being to render 10 said pipes and cocks air-tight and easily connected and disconnected. This object I attain by the mechanism shown in the accompanying drawings, in which—

Figure 1 is a vertical longitudinal section showing a method of forming joints to connect vacuum-pipes to a "fork-socket," also 20 showing the lower end of a fork. Fig. 2 is an elevation of the same. Fig. 3 is a vertical longitudinal section showing my device as applied to a cock. Fig. 4 is an elevation 25 of the same.

In the drawings, A and A' represent the pipe that leads from a vacuum-pump to the lamps to be exhausted.

E and E' are jacketing-pipes made so much 30 larger than the vacuum-pipe as to leave a space S between the two, as shown. This space S may be filled with oil or some of the fluid adapted for the purpose of sealing joints, &c., or the space may be a vacuum in 35 connection with an auxiliary pump.

C C' represent a jacketing-case connected to the pipes E and E' by the following described device:

E² is a thimble having an external screw- 40 thread cut on each end, as shown. The ends of this thimble E² are internally coned, so that the packing K and K' may be forced partly into them—that is, between the ends of the thimble and the pipe E' on the one 45 side and the part C² of the jacketing-case on the other.

F and F' are screw-collars adapted to engage with the screw-thread on the ends of the thimble E² and coned interiorly, so as to 50 embrace the packings K and K'.

As the several joints shown in the drawings are all like the one just described, they need not be explained.

The jacketing-case C has a bottom C³ 55 screwed into it, as shown, and at the top has an annular member C⁴ projecting from its interior wall. This annular member serves as a buttress for supporting the socket-piece B, said socket-piece being held firmly in place by the screw-follower B⁷. The upper open 60 end of the jacketing-case is cupped for holding any suitable sealing-fluid.

In Figs. 1 and 2 I have shown in connection with my device the socket end P of a fork, such as are made by glass-blowers for 65 connecting the bulbs of incandescent lamps to the vacuum-pump, and fits by a ground-joint F² into the socket-piece B. A similar device may be used for connecting the vacuum-socket B to any article to be exhausted. 70

In case this device is to be used for a part 75 of a stop-cock, then a key D, Figs. 3 and 4, is to be used. This key D has a handle H and a transverse opening D' for the purpose of connecting the passage in the vacuum-pipes A and A' when desired. A small opening d is made in the key D, extending from the transverse opening D' to the lower end 80 of the key. This opening d allows the otherwise imprisoned air or liquid below the end of the key to escape, otherwise it is found difficult to make the key stay in place.

Having thus fully described my device, what I consider as new, and wish to secure by Letters Patent, is—

In connection with a system of vacuum-pipes, the combination of a socket-piece 85 adapted to receive a key or the socket end of a fork, and having passage-connections with the vacuum system, with the jacketing-piece C, having passage-connection with a jacketing system as described, substantially as and for the purpose set forth.

ADOLPH BERRENBERG.
